UNITED STATES PATENT OFFICE.

ANDREW R. RIDDERSTROM, OF NAHANT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SKIVING MACHINE.

Application filed December 9, 1921. Serial No. 521,239.

The present invention relates more particularly to machines for skiving the margins of sheet material, like leather or other stock adapted for use in the manufacture 5 of boots and shoes, but embodies features of more general application the nature of which will appear in the course of the following description and will be particularly pointed out in the claims.

10 In skiving machines of the above-described character, the shoe upper is usually advanced by a feed roll and a feed disk to a rotating skiving knife which cuts a scarf in the margin of the material. In some 15 types of skiving machines of this character, such as in the machine constituting the subject matter of a copending application, Serial No. 319,565, filed August 25, 1919, the knife shaft and the feed-element shafts are 20 geared to, and are driven from, a common driving shaft. Machines of this type are satisfactory in operation, but can not be driven at too high a speed. This is principally because the comparatively low-speed 25 gear upon the driving shaft is relied upon to drive the gear upon the knife-shaft at very much higher speed; and the character of the consequent strain imposed upon the gearing is made evident by the racket and 30 the grinding noise thereby produced. At very high knife speeds, therefore, the gearing connections between the knife shaft and the driving shaft become overheated, and if such prohibitive speeds be persisted in, 35 these gears will burn out altogether.

It is accordingly an object of the present invention to improve upon machines of the above-described character, to the end that their speed of operation may be materially 40 increased.

With this end in view, a feature of the invention resides in driving the knife shaft by a belt direct from a source of driving power, and driving the feed elements from 45 the knife shaft. Instead of driving the knife shaft at comparatively high speed, through gearing, from the driving shaft, therefore, as in the machine of the above-described application, the latter shaft is 50 driven at comparatively low speed, through gearing, from the independently driven, high-speed, knife shaft. There is obviously less strain involved when driving a low-speed gear from a high-speed gear than

when it is attempted to drive a gear at high 55 speed from a gear that is operating at low speed. Overheating and consequent destruction of the gears is thereby prevented, and it becomes possible to operate the machine at as high a speed as the strength 60 of the materials will permit without rupture caused by centrifugal force.

To overcome the above-described difficulty, the knife has heretofore been independently driven, in some types of machines, by a belt from a pulley secured to the main driving shaft, the latter, of course, being belt-driven from some source of power 65 to drive the feed elements independently of the knife. According to the present invention, the gear connection between the knife shaft and the driving shaft is retained, and the main driving belt is directly connected 70 to the knife shaft.

The shafts of belt-driven knives have a 75 tendency to wear semi-oval-shaped recesses in their bearings, resulting in looseness and vibration; and this, in turn, causes uneven skiving. To minimize the effect, flat seam- 80 less, expensive driving belts are provided, as seams and attendant belt hooks would cause jarring of the knife shaft every time that they went around the shaft.

It is therefore a further object of the invention to provide an improved mounting 85 for the knife shaft that shall avoid these difficulties.

In the specific embodiment of the invention that is herein illustrated and described, this result is attained by mounting the knife 90 shaft in a stationary bearing that is, in turn, mounted in a rotatable bearing that is provided with the driving pulley. The last-named bearing is locked to the knife so as to drive the latter, the knife shaft being 95 driven from the knife, and not, as has been customary hitherto, the knife from the knife shaft. The knife shaft is therefore not subjected to the customary uneven strain encountered in present-day-machines, and the 100 bearings therefore wear down evenly.

It is desirable to vary the rate of feed of the feed elements of skiving machines, sometimes manually, and at other times automatically in accordance with the nature of 105 the article operated upon. It has heretofore been proposed to effect such rate variation by providing a yielding friction clutch be-

tween the knife-driving pulley and the shaft upon which it is mounted and that drives the feed elements. The feed means are thus driven yieldingly from the knife. According as the friction elements of the clutch are pressed together more or less firmly, the shaft will be driven at higher or lower speed with consequent more or less rapid operation of the feed elements. The clutch is supposed to slip automatically when abnormal loads are imposed upon the feed means. In the heretofore suggested embodiments of this proposal, the knife-driving pulley was pushed back and forth along the shaft into firmer and less firm clutching engagement with the shaft, as was desired.

A serious objection to this method of feed control is that it is not sensitive. As the knife-driving pulley, together with the belt that drives it and the knife-driving belt that it drives, are moving at high speed, and have a consequent high inertia, it is somewhat difficult to move the pulley backward and forward along the shaft, and almost impossible to make it respond quickly. At least one of the belts, furthermore, has a tendency to wobble somewhat over the face of the pulley, thereby automatically causing the friction elements of the clutch to press together now a little less heavily than is required, and then a little too heavily. This, of course, has a tendency to produce a somewhat jerky feed movement that it is difficult to control.

It is another object of the present invention, therefore, to provide an improved variable feed for skiving machines of this character.

To this end, a feature of the invention resides in clutching the knife and the feed shaft together through comparatively low-speed mechanism having comparatively little inertia.

As the leather or other stock that is used for shoe uppers is usually of varying thickness, the feed disk of a commercial skiving machine is permitted to yield in a direction along its axis of rotation, so as to cut a scarf of uniform width in the edge of the stock. Along with the disk moves the spindle upon which it is mounted and, sometimes, other mechanism as well. The added weight decreases the sensitiveness of the device.

Another object of the present invention, therefore, is to improve the sensitiveness of the feed disk.

With this end in view, the feed disk is permitted to tilt at an angle to its axis of rotation. When parts of the stock of greater than uniform thickness are encountered, therefore, the feed disk alone yields. The feed disk is at other times resiliently maintained in its normal position.

With the above and other objects in view, the invention consists of the improved ma-

chine hereinafter described, illustrated in the accompanying drawings, and defined in the appended claims.

In the drawings, Fig. 1 is a rear elevation of a machine constructed according to a preferred embodiment of the present invention; Fig. 2 is a plan of the same; Fig. 3 is a longitudinal, central, vertical section, taken upon the line 3—3 of Fig. 2, looking in the direction of the arrows, with parts in elevation and other parts omitted for clearness; Fig. 4 is a side elevation showing a preferred gauge and guide; Fig. 5 is a central, vertical section of the forward part of the machine, taken upon the line 5—5 of Fig. 2, looking in the direction of the arrows; Figs. 6 and 7 are sections taken upon the line 6—6 and 7—7, respectively, of Fig. 5, looking in the direction of the arrows; Fig. 8 is a detail elevation, partly in section; Fig. 9 is a section taken upon the line 9—9 of Fig. 3, looking in the direction of the arrows; Figs. 10, 11 and 12 are views taken along the lines 10—10, 11—11 and 12—12, respectively, of Fig. 1, looking in the direction of the arrows; Fig. 13 is an elevation of a preferred power transmitter; Fig. 14 is a section taken upon the line 14—14 of Fig. 13, looking in the direction of the arrows; Fig. 15 is a section taken upon the line 15—15 of Fig. 14, looking in the direction of the arrows; and Fig. 16 is a section taken upon the line 16—16 of Fig. 5, looking in the direction of the arrows.

The invention is for illustrative purposes shown in the accompanying drawings as embodied in a machine having many features in common with the machine of the above-identified application, and that do not, in themselves, constitute any part of the present invention. It will conduce to clearness to describe some of these common features in advance of, and as a setting for, the explanation of the features that more particularly relate to the present improvement.

The main frame, represented by the numeral 20, is provided with a base portion 21 which may be bolted to a bench or the like and which is also provided with an overhanging arm or head 22 projecting over the base, as will be understood from an inspection of Fig. 3. The overhanging arm 22 carries a skiving knife 185 and a feed disk 143, and houses driving means therefor. The base portion houses the feed-roll mechanism and the drive elements therefor, the feed roll 95 itself projecting forwardly beyond the base portion.

At the top, and to the rear, of the main frame 20 is a main bearing 25, Fig. 3, extending longitudinally of the head 22. At the front end of the said head is a projection or lug 26 provided with another main

bearing 27 fastened thereto by the screws 28. The first-named bearing 25 is provided with a bearing sleeve 30 of a length greater than the bearing and the projecting end of the said sleeve serves the function of supporting a bracket 68. A shaft 32 is journaled in the sleeve 30 and the bearing 27. This shaft corresponds to the main driving shaft of the above-mentioned application, 10 but will herein be referred to as the feed shaft, as the feed roll and the feed disk are driven therefrom. The feed shaft 32 is adapted to be driven from the knife shaft, as will be explained hereinafter, through a 15 clutch 44, 45 between the feed elements and the knife.

A worm 62 is secured to the feed shaft 32, at the said projecting end of the sleeve 30. The bracket 68 is provided with bearings 20 72 and 73 within which is journaled a shaft 78 that is transversely disposed to the feed shaft 32. Secured to the upper end of the shaft 78 is a worm gear (not shown) that meshes with the worm 62 and is rotated 25 thereby. Secured to the lower end of the said shaft 78, beneath the bearing 73, is a spiral gear (not shown) that meshes with a transversely disposed spiral gear 81. The gear 81 is secured to a feed-roll shaft 83 30 that is journaled in an oscillative bearing 84 and in bearings 85 and 85^a through a sub-frame 86. The bearing 84 may be slightly rounded or slightly tapering from the middle 87 thereof towards each end, or in an 35 axial direction, so that the same can be rocked within the bore 88 through the hub 89 that projects inwardly of the frame 20. Axial and rotatable movements of the bearing are prevented by means shown with 40 more particularity in the above-identified application, but an upward and downward or a rocking movement are permitted. The shaft 83 may therefore be rocked upward or downward for adjustment or other purposes, by an adjusting screw 101, a spring 107 45 maintaining the feed roll comparatively fixed under ordinary working conditions, so as to preserve the width of the scarf uniform. The feed roll will, of course, yield 50 also under exceptional circumstances, as when the leather becomes bunched during its passage through the machine.

The shaft 83 may also be moved axially, to adjust the position of the feed roll 95, 55 whereby the length of the scarf may be varied, by a threaded shaft 113 provided with a knurled head 115, acting in opposition to a spring 116. During this axial adjustment, the spiral gear 81 will move downward slightly with respect to the gear (not shown) with which it meshes that is provided on the lower end of the shaft 78, and the teeth of the gears will slip slightly with 60 respect to each other without unmeshing. 65 The driving and the driven mechanisms of

the feed roll are thus constructed to cooperate in all positions of adjustment, and the speed and the power of the drive will remain unaffected. The associated and co-operating parts permit of the above-described yielding and universal adjustments both downward and axially, the screw 101 providing for vertical adjustments of the feed roll, and the threaded shaft 113 for the axial adjustments. 70

The preferred guide and gage 131 for co-operating with the feed roll 95 and the knife 185 to guide the work is shown in Fig. 4, but is not described herein because it forms no essential part of this invention. The 80 gage limits the extent of the scarf, so that each separate piece of work shall be skived uniformly and to the same extent as all other work of the same class. The gauge and guide shown may be adjusted close to 85 the skiving knife 185 and, being yielding both vertically and in either direction about an intermediately disposed pivot 129, variations of thickness of leather presented between the same and the feed roll 95 will be 90 automatically taken care of and the scarf will start close to the guiding clamp and will also terminate close thereto. It is adapted to press the leather or other stock 95 yieldingly against the feed roll.

To the extreme left-hand end of the feed shaft 32, see Figs. 3 and 5, and suitably secured thereto, is a worm 135. This worm meshes with a worm gear 136 that is keyed or bolted to the upper end of the feed-disk 100 shaft 137. The shaft 137 is journaled at 138 and 139 in an adjustable bearing 140. The feed disk 143 normally presents an angular working relation with respect to the feed roll 95, and the driving gearing is such 105 that both axial and transverse movement may be had between the gears without disengagement thereof either for adjustments or when performing work, the teeth of the gear 136 merely slipping through the teeth 110 of the worm 135.

The feed roll 95, the driving connections between the feed shaft 32 and the feed roll and the feed disk 143, and the gauge and guide 131, are the same as shown in the above-described application, and do not, in themselves, constitute any part of the present invention. They are shown in the accompanying drawings because they form part of the illustrative machine, and they are briefly described 115 above simply as a preliminary to an understanding of the description that is to follow. Machines embodying other feed rolls and feed disks and driving connections, and other types of gauges and guides and the like, may equally well embody the improvements constituting the present invention. 120

In the above-mentioned application, the knife 185, as well as the feed roll 95 and the feed disk 143, is shown as geared to, and 130

driven from, the shaft 32, which is thus the main driving shaft. According to the present invention, however, the knife is directly driven by a belt 1, and the shaft 32, that drives the feed roll and the feed shaft, is driven from the knife.

A flanged collar 183 is fastened in any well known manner to the lower end of the knife shaft 181. The knife 185, shown circular or of disk shape, is secured to the flange of the collar by means of a clamp screw or the like 186, and relative rotative movement of the knife and the collar is prevented by a dowel pin 145. The upper end of the knife shaft is provided with a worm 182. This worm meshes with the worm-gear portion of an elongated gear member 163 that is freely rotatable upon a stationary rod 164. The worm-gear portion of the gear member 163, with which the worm 182 meshes, is at the rear of this gear member 163, as will be understood from an inspection of Fig. 16. The front portion of the gear member 163 constitutes a spiral gear that meshes with a spiral gear 162, shown to the right of the bearing 27, Figs. 3 and 5. The gear 162 is mounted upon a hollow shaft 2 through which the feed shaft 32 extends. The hollow shaft is freely rotatable with respect to the feed shaft 32, but the two shafts are adapted to be clutched together to rotate as a unit. The knife shaft 181 is thus adapted to drive the feed elements 95 and 143 through the gears 182, 163 and 162.

The dimensions of the gears 182, 163 and 162, as will be clear from the drawings, are such that the gear 182 may operate at comparatively high speed while the gear 162 is operating at comparatively low speed. In the machine of the above-described application, the gear 162, driven at low speed by the shaft 32, effects the operation at high speed of the knife shaft 181 and the gear 182 carried thereby. This speed transmission from the gear 162 to the gear 182 is attended by considerable grinding noise; and if the machine is driven at too high a speed, the gearing may actually catch fire. By running the knife shaft 181 originally at high speed through the belt 1, however, the worm 182 is directly driven at high speed, and stepping down from this high speed to the low speed of the gear 162 is attended with a minimum of noise and without overheating the parts. This result is greatly aided by making the pinion 182 and the intermeshing portion of the pinion 163 as worm gears instead of spirals, as in the above-identified application. Spirals, in the particular location indicated, could not be driven at so high a speed. It is thus possible to run the machine at as high a speed as is consistent with the strength of the materials employed in building the ma-

chine. The speed of the knife may thus be increased to 10,000 revolutions per minute, keeping the rate of feed the same as in the above-mentioned application.

One of the difficulties experienced with belt-driven knife shafts of commercial skiving machines has been the tendency of the shaft to veer too much to one side, wearing the shaft bearing unevenly, or semi-oval in shape, and resulting in looseness and consequent rattling and vibration of the shaft in its bearing. According to the present invention, this difficulty is eliminated by protecting the knife shaft against direct thrust from the belt. The knife shaft 181 is mounted in a bearing 180 that is keyed or otherwise firmly mounted in a knife bracket 170 at 3. The pulley 4 that is driven by the belt 1 is loosely mounted about the bearing 180. The pulley 4 is therefore not directly connected to the knife shaft, as is customary in skiving machines embodying belt-driven knives. The pulley is connected or locked directly to the knife 185 instead, so that the knife shaft is driven by the knife instead of, as is usual, the knife by the knife shaft. To this end, the sleeve 5 that is integral with the pulley is, in the illustrative machine, shown as oppositely recessed at 6 to receive oppositely disposed, upstanding lugs 7 that are provided upon the flanged knife collar 183. Rotative movement of the pulley is thus necessarily communicated to the knife; and from the knife, thus indirectly, to the knife shaft 181. The knife shaft is thus enabled to rotate freely and smoothly in its bearing 180 without rattling or vibration, and without wearing any part of the bearing unevenly. The recesses 6 are for convenience, in practice, made a little wider than the lugs 7, this introducing no undesirable effects from back lash because the knife is always rotated in the same direction, as indicated by the arrow in Fig. 2.

The knife is further prevented from rattling or vibrating during its rotation by the fact that the knife shaft 181 is maintained snugly fitted in its bearing 180 during the rotation of the shaft. As the gear 182 drives the gear 163, it is obvious, from the angle of the worm threads shown in Fig. 5, that the shaft 181 will be maintained in raised position during the rotation of the shaft. A conical projection 8 of the shaft will thus be maintained in snug engagement with a conically enlarged recess 9 of the bearing.

The flat, seamless belts of present-day belt-driven knives are expensive, and they are mounted over corresponding flat-faced pulleys, to eliminate as much as possible the jar and vibration effects. The construction of the present invention permits using the ordinary, round, seam belt, the ends of which are connected by a hook or hooks, and the

ordinary pulley shown in Fig. 5, without any jarring or vibration.

For purposes of ready assembly, the bearing 180 is provided with an annular shoulder 10 upon which rests the pulley 4, the pulley being confined between the shoulder and a wall 11 of the bracket 170. A tube 12 serves to conceal the sleeve portion 13 of the pulley 4 that overhangs the lower portion of the bearing 180 and the upper portion of the flange 183.

As in the machine of the above-referred-to application, provision is made for relatively adjusting, at will, the angular positions of the skiving knife and the feed roll, during the operation of the machine, to a substantial extent sufficient to meet commercial needs, so that the operator, after skiving a scarf of one angle in a portion of the 20 margin of the leather, is enabled quickly to change the angular relation of the knife and the feed roll. Scarfs of different angle may thus be quickly produced in different portions of the margin of the same 25 upper by using the same machine and before the article has left the operator's hands. To this end, the knife bracket 170 is angularly adjustable about the rod 164, being provided with oppositely disposed bearings, one of which is shown at 171, within 30 which the rod 164 is journaled. The knife bracket is also adjustable transversely of the feed roll 95 by means including a plunger 176, but this is not further described herein 35 because it does not form any essential part of the present invention. A finger or lug 188 that projects from the knife bracket is yieldingly engaged by a dog 17 through the 40 action of a spring 189. The spring thus tends to maintain the lug 188 in engagement with a limiting stop 190. The position of the stop 190 may be adjusted by an adjusting screw 191 that is tapped in the head 22 of the machine and that engages a shoulder 192 of the stop 190. Adjustment of the screw 191 will therefore result in 45 rotatably adjusting, about the rod 164, the angular position of the knife bracket 170 and the knife 185 that is mounted thereon, the spring 189 acting always to maintain 50 the lug 188 in engagement with the adjustable stop 190. The pinions 163 and 182 are maintained in meshing engagement irrespective of the angularly adjusted position 55 of the bracket 170 and the skiving knife 185. The knife may therefore be adjusted to any angular position relatively to the work face 127 of the feed roll 95 during the operation of the machine without disturbing 60 the meshing of the pinions 163 and 182. By means of the above-described construction, the spring 189 exerts a force upon the knife shaft in the same angular direction as the belt 1, each acting to maintain the lug 65 188 in engagement with the stop 190.

The mechanism for clutching the feed shaft 32 to the hollow shaft 2 will now be explained. An end of the hollow shaft 2 is provided with a clutch element 44, shown as a friction disk, that is adapted to co-operate with another friction clutch element 45 that is non-rotatably mounted upon the shaft 32. Sliding movement of the clutch element 45 towards and away from the clutch element 44 is permitted by an elongated opening 15, Fig. 9, that is longitudinally provided in the shaft 32, and through which extends a bolt or pin 16 that is rigidly secured to the clutch element 45. The clutch elements 44 and 45 are normally maintained separated by a spring 40. The clutch element 45 may be forced into frictional clutching engagement with the clutch element 44, in opposition to the action of the spring 40, by a friction-plug rod 46 that is 80 slidably mounted within a hollow end portion 38 of the shaft 32. To this end, the rod 46 is adapted to be engaged by a friction plug 47 at the end of an arm 48 of a bell-crank lever 49. The lever 49 is intermediately pivoted at 50 between ears 51 of the frame 20. Pivotal movement of the lever 49 will thus result in the rod 46 being moved inward, in opposition to the force of the spring 40, causing the clutch elements 95 to engage frictionally, as above described. The feed shaft 32 may thus be driven from the knife shaft 181. To effect the actuation of the bell-crank lever 49, its end 52 is pivotally connected at 53 to an actuating rod 100 54 that extends downward through the frame 20 to a foot-operated treadle (not shown).

Upon the release of the treadle (not shown), the bell-crank lever 49 is returned 105 to its normal position by a spring 14, as will be understood from Fig. 3. The spring 40 will thereupon separate the clutch elements 44 and 45. At the same time, the friction face 56 of a brake member 55 will engage 110 a hand wheel 34 that is secured to the hollow portion 38 of the feed shaft 32 to stop the further rotation of the feed shaft. The brake 55 is pivotally mounted at 50, and its braking action may be adjusted by a screw 115 59 that is threadedly mounted upon the bell-crank lever 49.

As the clutch elements 44 and 45 are pressed together more or less firmly, the feed elements may be driven at higher or lower 120 speed, at the will of the operator. The rate of feed is also controlled automatically by the character of the work operated upon. Work of normal characteristics is fed through the machine at a speed predetermined by the operator, the clutch elements 44 and 45 being under the control of his foot. When abnormally thick stock is encountered, however, the clutch elements 44 and 45 of the yielding clutch may slip automatically to 125 130

produce a correspondingly lower speed. The degree of slip will depend somewhat upon the tension of the spring 107, which may be adjusted to produce the desired results.

The above-described feed control is found to be very sensitive in practice. The response of the low-inertia movable clutch element 45 to movements of the operator's foot is immediate, and very light pressure of the foot effects this response and maintains the clutch elements 44 and 45 actively engaged.

The present invention embodies also a novel feed disk. Feed disks have heretofore been constructed to yield axially, disk, shaft or spindle, and all. This is not a sensitive construction. According to the present invention, the disk is caused to tilt yieldingly about an axis transverse to the feed-disk shaft, resulting in very sensitive response to abnormal conditions. The feed-disk shaft 137 is rigidly clamped against longitudinal movement by nuts shown at the top of the shaft, the customary axial-yielding-permitting spring being omitted. The nuts permit adjusting the feed-disk shaft longitudinally to adjust the position of the feed disk.

The feed disk 143 is mounted at the lower end of the feed-disk shaft 137 through the medium of a threaded screw 144 that is threaded into a correspondingly threaded bore provided in the lower end of the shaft 137. The feed disk is adapted to tilt or pivot about the head 18 of the screw 144, in the direction of the arrow, Fig. 5, towards the knife 185 and away from the feed roll 95. In order that this tilting or pivotal movement may be as frictionless as possible, the head 18 of the screw 144 is ball-shaped, and the walls of the chamber 19 within which it is confined are shaped to correspond. For convenience of assembly, these walls are formed at 23 on the feed disk and on separable plates 24 that are secured to the feed disk, with the ball head 18 between them, by screws 29. Lugs 31 projecting from the ball head 18 engage the walls of suitable recesses in the plates 24 to cause the feed disk to rotate with the shaft 137 upon which it is mounted.

A plunger 33 is forced by a spring 37 into engagement with the feed disk to oppose yieldingly the tilting movement of the feed disk and to maintain the feed disk at right angles to its shaft. The force of the spring 37 may be adjusted by a collar 41 that is threadedly adjustable upon threads 57 that are integrally provided upon the bearing 140. The plunger 33 is mounted in a split collar 142 that is clamped to the lower portion of the bearing 140, below the threads 57, by a clamping screw 141. A key 245 provided upon the said lower portion of the bearing 140 is seated in a corresponding groove of the clamp 142 to prevent acci-

dental rotation of the clamp 142, thus determining the point on the feed roll 95 at which the feed disk 143 shall tilt. The clamp 142 is slantingly cut away, as shown in Fig. 3, to permit the feed disk to tilt.

The present invention, then, comprises an independently driven knife through which the feed elements may be driven. The knife may be continuously rotating or it may be at rest, at the will of the operator; and during the rotation of the knife, the feed elements may be set into operation, or brought to rest, at the will of the operator. The invention comprises also a novel transmitter for controlling the rotation of the knife, whereby it may be connected to, and disconnected from, a source of power. This will now be described.

The belt 1 that drives the knife pulley 14 passes over idler pulleys 260 and 262, in the direction of the arrows, and over a cone pulley 264 that may be driven from any suitable source of power by a belt 266. The belt 266 is shown in Fig. 14 mounted over a fast pulley 268. The cone pulley 264, the fast pulley 268 and a loose pulley 270 are mounted upon a common shaft 272. The belt 266 may be shifted from the fast to the loose pulley, or from the loose to the fast, by a belt shifter 274. To shift the belt 266 from the fast pulley to the loose pulley, the operator presses down upon the belt shifter 274 in the direction of the arrows, Figs. 13 and 15, and moves the lever over from the full-line position to the dotted-line position of Fig. 15. Operators sometimes carelessly neglect to move a belt shifter all the way over, with the result, in the present instance, that the knife may continue to operate at a time when it should be at rest, which might result in accident, besides loss of power. A spring 276 is therefore provided to positively insure that the belt shifter shall shift the belt the whole required distance. In fact, all the operator need do is to press down upon the belt shifter, in the direction of the arrows, Figs. 13 and 15, and the spring 276 will do the rest. The spring 276 maintains the belt shifter 274 tightly against a lug 278 or a lug 280, maintaining it against accidental displacement from the position in which the belt 266 is over the fast pulley 268, or the position in which the belt 266 is over the loose pulley 270, as the case may be. This last-described action of the spring 276 is aided by a spring 282 that tends to maintain the belt shifter tightly against the under face of a lever in the form of a board 284, to which it is intermediately pivoted at 286. The board 284 is pivotally adjustable about a point 288, and it may be clamped in adjusted position by a screw 290 and a nut 292. A bracket 294 that carries the shaft 272 is integral with the board 284, the bracket and the board, in effect,

constituting a bent lever that is intermediately pivoted at 288. The above-described pivotal adjustment of the board 284 therefore effects a transverse adjustment of the shaft 272 and the cone pulley and the fast and the loose pulleys that are mounted thereon, providing for tensioning the belt 266.

The pulley 262 is carried upon a bracket 263, Fig. 10, that may be adjustably clamped to the base portion 21 of the frame of the machine by a bolt or screw 265 that is adapted to enter any one of three openings 269, 271 and 273. The pulley 262 may thus be adjustably positioned over the small, the medium-sized and the large portion, respectively, of the cone pulley 264. The pulley 262 may thus be driven from the cone pulley 264 at any of three speeds.

Provision is made for adjusting the tension of the belt 1 by adjusting the position of the idler pulley 260. The idler pulley 260 is therefore journaled upon the free end of an arm 296 the other end of which is pivoted at 298 to a bracket 300. The bracket 300 may be secured to the frame of the machine in any desired manner, as by means of screws 302. A spring 304, Fig. 1, coiled about a threaded rod 306 forces the arm 296 outwardly, causing the pulley 260 to act as a belt tightener. The force of the spring 304 may be adjusted by threadedly adjusting the rod 306, a check nut 308 serving to lock the rod 306 in adjusted position. To provide for free action of the spring against the arm 296, the arm is intermediately curved at 310, and the curved portion is engaged by a curved washer that is yieldingly forced into such engagement by the spring 304.

A pulley 251, Figs. 1 and 10, that is fast to the pulley 262, serves as a source of driving power for a grinder disk 194. The grinder disk is fixed to a flanged collar 195 of a grinder shaft 196 by a set screw or the like 197. The flanged collar 195 is fixed to the shaft 196 by a pin or the like 198. Adjacent to the collar, the shaft is provided with a frusto-conical bearing portion (not shown) adapted to seat in a similarly shaped bearing 199. The bearing 199 is adjustably clamped in a split socket 203 by the bolts 204 passing through one lug 205 and tapped into the lug 206 on opposite sides of the split 207, Figs. 1 and 2. The socket 203 is mounted upon a divided rocker arm 218 that is pivoted about a bearing rod 222. The grinder 194 is adjustable vertically, laterally and transversely in a manner described in the above-named application, and it may be moved into and out of grinding relation to the skiving knife 185 about the bearing rod 222 by manipulating a handle 242, Fig. 2, that is secured to the rocker arm 218.

A pulley 200 that is secured to the shaft 196, above the bearing 199, is driven by a

belt 245 that passes from the pulley 251, over idler pulleys 246. In order that the belt 245 may be tightened or loosened, as desired, the idler pulleys 246 are made adjustable. To this end, they are rotatably mounted upon a bracket 247 that is pivoted to the frame of the machine at 248, Figs. 1 and 12. In order that the bracket 247 may be held in pivotally adjusted position, it is provided with a toothed catch 250 the teeth of which are adapted to engage a lug 314. The bracket 247 is provided with a handle, whereby it may be manually pivoted about the pivotal point 248, the catch 250 falling by gravity about a pivotal point 316 of the bracket into adjustable engagement with the lug 314.

A very much simpler belt-tightener for the belt 245 is thus provided than in the above-identified application. Ordinarily, however, the belt-tightener will seldom be called into play, the belt automatically tightening and becoming slack in accordance with the position that the grinder 194 happens to occupy. When the grinder is moved away from the knife, about the rod 222, the belt will naturally slacken because the pulley 200 will then be nearer to the idler pulleys 246 than in the position illustrated by Figs. 1 and 2. The grinder may thus be started rotating and swung into position against the knife by a single operation, and a single operation similarly stops the grinder rotating and swings it out of operative position.

The description of many portions of the machine an understanding of which is not essential to an understanding of the present invention has purposely been made very brief in order not to distract the attention from the features of essential novelty. Fuller explanation of such portions of the machine will be found in the copending application referred to above. It will be clear that the features of novelty may be embodied in other machines, and in machines of other types, and that modifications may be made therein by persons skilled in the art, without departing from the spirit and scope of the invention, as defined in the appended claims.

What is claimed as new is:

1. A skiving machine having, in combination, a shaft having a disk knife, means for driving the shaft, two shafts having a feed roll and a feed disk, respectively, for feeding material to the knife, a feed shaft with which the feed-roll shaft and the feed-disk shaft are connected so as to be driven therefrom, and means connecting the feed shaft with the knife shaft to cause the feed shaft to be driven from the knife shaft.

2. A skiving machine having, in combination, a shaft having a disk knife, means for driving the shaft, means comprising a feed roll and a feed disk for feeding material to

the knife, means connecting the feed means with the shaft to cause the feed means to be driven from the shaft, the connecting means comprising a clutch, and means for controlling the clutch to drive the feed means or bring the feed means to rest, at will, during the operation of the machine.

3. A skiving machine having, in combination, a shaft having a disk knife, means for driving the shaft, two shafts having a feed roll and a feed disk, respectively, for feeding material to the knife, a feed shaft with which the feed-roll shaft and the feed-disk shaft are connected so as to be driven therefrom, means connecting the feed shaft with the knife shaft to cause the feed shaft to be driven from the knife shaft, and a clutch between the last-named means and the feed shaft, whereby the feed means may be driven or brought to rest, at will, during the operation of the knife.

4. A skiving machine having, in combination, a shaft having a knife and a gear, means for driving the shaft, a shaft having a clutch element and a gear connected to the knife-shaft gear, a shaft having a co-operating clutch element and two gears, a shaft having a feed disk and a gear meshing with one of the two gears, a shaft having a feed roll and a gear, and a shaft having a gear meshing with the feed-roll-shaft gear and the other of the two gears.

5. A machine of the class described having, in combination, a bearing, a shaft mounted in the bearing having a knife and a gear, means for feeding material to the knife, means comprising a gear meshing with the shaft gear for driving the feed means, the meshing gear being driven from the shaft gear at a speed lower than the speed of the shaft gear, the shaft having a conically enlarged portion, and the bearing having a conical recess to receive the conically enlarged portion, whereby the shaft is maintained with the conically enlarged portion in tight engagement with the walls of the conical recess during the rotation of the shaft, a pulley mounted about the bearing, and means connecting the pulley to the knife to cause them to rotate together with the shaft when the pulley is driven.

6. A skiving machine having, in combination, a rotary knife, two shafts having a feed roll and a feed disk, respectively, for feeding material to the knife, and means whereby the feed disk is adapted to tilt about the feed-disk shaft.

7. A machine of the class described having, in combination, means for feeding material comprising a feed disk rotatable about an axis, and means whereby the disk as a unit is adapted to tilt yieldingly at an angle to the axis.

8. A skiving machine having, in combination, a rotary knife, two shafts having a feed

roll and a feed disk, respectively, for feeding material to the knife, means whereby the feed disk is adapted to tilt about the feed-disk shaft, means yieldingly opposing the tilting movement, and means for adjusting the opposing means.

9. A machine of the class described having, in combination, a rotary shaft the end of which is provided with a screw-threaded bore, a screw threaded in the bore, an element tiltingly mounted upon the screw, whereby the element may tilt about the screw during the rotation of the shaft and means yieldingly opposing the tilting movement of the element.

10. A machine of the class described having, in combination, a shaft having a knife, means for feeding material to the knife comprising a feed roll and a feed disk rotatable about an axis, means normally maintaining the disk yieldingly at right angles to its axis, and means whereby the feed disk is adapted to tilt at an angle to its axis.

11. A machine of the class described having, in combination, a shaft having a knife and a belt-driven pulley, means for angularly adjusting the shaft, and means yieldingly maintaining the shaft in adjusted position, the yielding means exerting a force upon the shaft in the same angular direction as the belt.

12. A machine of the class described having, in combination, rotatable feed means, means whereby the rotatable feed means is adapted to tilt about an axis inclined to the axis of rotation of the shaft, means yieldingly opposing the tilting movement, and means for preventing the displacement of the yielding opposing means.

13. A skiving machine having, in combination, a shaft having a knife and a worm, a gear member having two portions one of which constitutes a worm meshing with the shaft worm, means for feeding material to the knife, a shaft for driving the feed means having a gear meshing with another portion of the gear member, and means for driving the knife shaft, whereby the feed means is driven from the knife shaft.

14. A machine of the class described having, in combination, a bearing, a shaft mounted in the bearing and having a knife, a pulley mounted about the bearing and directly connected to the knife, and a belt for driving the pulley, whereby the knife shaft is driven by the pulley from the knife.

15. A machine of the class described having, in combination, a bearing, a shaft mounted in the bearing and having a knife, a pulley mounted about the bearing having a recessed sleeve, the knife having a lug adapted to be received in the recess of the sleeve, and a belt for driving the pulley.

16. A machine of the class described having, in combination, a bearing having an

annular shoulder and a conical recess, a shaft mounted in the bearing having a conically enlarged portion received within the recess, the shaft having a knife, and a pulley 5 mounted about the bearing and directly connected to the knife, whereby the shaft is driven from the knife.

17. A machine of the class described having, in combination, a stationary bearing 10 having external and internal bearing portions, a shaft mounted in the bearing and bearing against the internal bearing portion, the shaft having a knife, driving means mounted about the bearing and bearing against the external bearing portion, and means connecting the driving means to the knife to cause them to rotate together with the shaft when the driving means is effective.

18. In a skiving machine having a skiving knife, two pulleys, a cone driving pulley having a plurality of different-size portions, a belt for driving the knife passing from one of the two pulleys to the cone pulley 25 and from the cone pulley to the other of the two pulleys, and means for adjusting the said one pulley so as to adapt it to cooperate with the different-size portions of the cone pulley without disturbing the position 30 of the belt relative to the pulleys.

19. In a skiving machine having a skiving knife, two pulleys, a driving pulley having a plurality of portions of different diameters, a belt for driving the knife passing 35 from one of the two pulleys to the driving pulley and from the driving pulley to the other of the two pulleys, and means for adjusting the position of the said one pulley in accordance with the position of the belt 40 upon the driving pulley.

20. In a skiving machine having a skiving knife, a driving pulley, a pulley driven from the driving pulley, a belt for driving the knife passing over the driven pulley and the driving pulley, means for adjusting the position 45 of the driven pulley in accordance with the position of the belt upon the driving pulley, a fast pulley for driving the driving pulley, a loose pulley, a second belt adapted to be mounted over the fast pulley or the loose pulley, a belt shifter for the second belt, a support for the fast and loose pulleys, the driving pulley and the belt shifter, means whereby the support may be adjusted to tension 50 the second belt, and means for maintaining the support in adjusted position.

21. In a skiving machine having a skiving knife, a driving pulley, a pulley driven from the driving pulley, a belt for driving the knife 60 passing over the driven pulley and the driving pulley, means for adjusting the position of the driven pulley in accordance with the position of the belt upon the driving pulley, a loose pulley, a fast pulley for driv-

ing the driving pulley, a second belt adapted to be mounted over the fast pulley or the loose pulley, a belt shifter for the second belt, and means for automatically actuating the belt shifter to shift the second belt to the loose pulley when it is actuated 70 to shift the second belt from the fast pulley.

22. In a skiving machine having a skiving knife, a driving pulley, a pulley driven from the driving pulley, a belt for driving the knife passing over the driven pulley and the driving pulley, means for adjusting the position of the driven pulley in accordance with the position of the belt upon the driving pulley, a loose pulley, a fast pulley, a second belt, 75 a belt shifter for the second belt, a stop against which the belt shifter is adapted to rest when the second belt is over the fast pulley, means yieldingly maintaining the belt shifter against the stop, and means for automatically actuating the belt shifter to shift 80 the second belt from the fast pulley to the loose pulley when the belt shifter is actuated away from the stop in opposition to the force of the yielding maintaining means.

23. In a skiving machine having a knife 90 and a grinder therefor, two pulleys, a third pulley, means for driving the third pulley, a belt for driving the knife passing from one of the two pulleys to the third pulley and from the third pulley to the other of the two pulleys, a pulley fast to the said one pulley, an idler pulley, a belt for driving the grinder passing over the idler pulley and the fast pulley, the idler pulley being adjustable, whereby it may serve as a belt-tightener, means for locking the belt-tightener in effective position, and means for unlocking the locking means to render the belt-tightener ineffective.

24. In a skiving machine having a skiving knife, a driving pulley, a pulley driven from the driving pulley, a belt for driving the knife passing over the driven pulley and the driving pulley, a pulley driven from the driven pulley, an idler pulley, a belt mounted over the third-named pulley and the idler pulley, the idler pulley being adjustable, whereby it may serve as a belt tightener, a catch pivoted to the idler pulley, and means adapted to be engaged by the catch to lock 110 the idler pulley in adjusted position.

25. In a skiving machine having a skiving knife, a driving pulley, a pulley driven from the driving pulley, a belt for driving the knife passing over the driven pulley and the driving pulley, a pulley driven from the driven pulley, a bracket having an idler pulley, a belt mounted over the third-named pulley and the idler pulley, the bracket having a handle whereby to adjust the idler pulley, thereby causing the idler pulley to serve as a belt tightener, a catch pivoted 120 to the bracket having a tooth, and means

adapted to be engaged by the tooth to lock the idler pulley in adjusted position.

26. In a skiving machine having a skiving knife, a driving pulley, a pulley driven from the driving pulley, a belt for driving the knife passing over the driven pulley and the driving pulley, a pulley driven from the driven pulley, an idler pulley, a belt mounted over the third-named pulley and the idler pulley, the idler pulley being adjustable, whereby it may serve as a belt tightener, a catch connected with the idler pulley, means adapted to be engaged by the catch to lock the idler pulley in adjusted position, and means maintaining the catch engaged with the locking means.

27. In a skiving machine having a skiving knife, a driving pulley, a pulley driven from the driving pulley, a belt for driving the knife passing over the driven pulley and the driving pulley, a fast pulley for driving the driving pulley, a loose pulley, a second belt adapted to be mounted over the fast pulley or the loose pulley, a belt shifter for the second belt, a support for the fast and the loose pulleys, the driving pulley and the belt shifter, means whereby the support may be adjusted to tension the second belt, and means for maintaining the support in adjusted position.

28. In a skiving machine having a skiving knife, a driving pulley, a pulley driven

from the driving pulley, a belt for driving the knife passing over the driven pulley and the driving pulley, a loose pulley, a fast pulley for driving the driving pulley, a second belt adapted to be mounted over the fast pulley or the loose pulley, a belt shifter for the second belt, and means for automatically actuating the belt shifter to shift the second belt to the loose pulley when it is actuated to shift the second belt from the fast pulley.

29. In a skiving machine having a skiving knife, a driving pulley, a pulley driven from the driving pulley, a belt for driving the knife passing over the driven pulley and the driving pulley, a loose pulley, a fast pulley for driving the driving pulley, a second belt adapted to be mounted over the fast pulley or the loose pulley, a belt shifter for the second belt, a stop against which the belt shifter is adapted to rest when the second belt is over the fast pulley, means yieldingly maintaining the belt shifter against the stop, and means for automatically actuating the belt shifter to shift the second belt from the fast pulley to the loose pulley when the belt shifter is actuated away from the stop in opposition to the force of the yielding maintaining means.

In testimony whereof, I have hereunto subscribed my name this 7th day of December, 1921.

ANDREW R. RIDDERSTROM.
